DOUBLE PRESSURE HYDRAULIC MACHINE
FOR HATS

Morris Schildhaus, New York, N. Y.

Application July 30, 1937, Serial No. 156,469

4 Claims. (Cl. 223—13)

This invention relates to new and useful improvements in a double pressure hydraulic machine for hats.

The invention has for an object the provision in a pressure hydraulic machine for hats, of a bottom forming section for supporting a hat having a crown portion and a brim portion, a top forming section cooperative with the bottom forming section to shape the hat form, and a novel construction of the top section for applying different pressures to the crown and to the brim portions of the hat form.

Heretofore, it was customary to arrange the top forming section with a single forming element which engaged the crown and the brim of a hat and which applied equal pressure to these parts.

Experiments have shown that a better hat can be produced if greater pressure is applied to the crown than to the brim. The crown requires a greater pressure since it must be stretched and formed to a greater degree. The brim requires smaller pressures to keep the texture of the hat material fine so that it feels good to the touch.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a front elevational view of a double pressure hydraulic machine for hats constructed according to this invention.

Fig. 2 is a fragmentary plan view of Fig. 1.

Fig. 3 is a fragmentary transverse sectional view taken on the center line of Fig. 2 but showing the piping for the hydraulic material, applied schematically.

Fig. 4 is a fragmentary horizontal sectional view taken on the line 4—4 of Fig. 3.

Fig. 5 is a fragmentary enlarged sectional view taken on the line 5—5 of Fig. 4.

Fig. 6 is a horizontal sectional view taken on the line 6—6 of Fig. 5.

Fig. 7 is an enlarged detailed view of a portion of the bottom forming section shown in Fig. 3 but illustrated inverted.

The double pressure hydraulic machine for hats, according to this invention, includes a bottom forming section 10 for supporting a hat having a crown portion and a brim portion, a top forming section 11^a, 11^b cooperative therewith, and means for forcing these sections together. The said top section is associated with a hollow cas-

ing 12 having an open bottom side and a central projecting portion 12^a. The part 11^b comprises a flexible crown forming element mounted on the bottom of the projection 12^a. The part 11^a comprises a flexible brim forming element mounted between the edge of said casing and on said projection. The parts 11^a and 11^b are preferably made of rubber and may be formed either in one or more pieces. A means is provided for supplying controlled hydraulic substance pressures to 10 said crown and brim forming elements.

The bottom forming section 10 is illustrated in detail in Fig. 7 and consists of a rubber or similar sheet material member 10^a formed in the shape of a hat having a crown and brim portion, 15 and covering sheets of felt material 10^b and 10^c upon the outer and inner faces thereof. The felt sheet 10^c extends over the brim portion of the member 10^a. The felt sheet 10^a extends over the crown portion only.

The bottom forming section 10 is rested on a support element 13 having a rubber covered top and inner portion 13^a. This element 13 is removably mounted upon a support member 14. It is held in correct relative position by pegs 15 cooperative between these parts. The support member 14 is supported on a carriage 16 which is provided with wheels 17 operating upon tracks 18 mounted on a body portion 19 of the machine. The carriage 16 is provided with a handle 20 by 30 which it may be drawn forward and moved rearward, as required.

The top forming section 12 is slidably supported upon the pair of vertical rods 22. More specifically, the said casing 12 has bearing portions 12^c 35 slidably engage the rods 22. The rods 22 extend upwards and support a stationary head portion 23. Between this head portion and the casing 12 there are a pair of spaced arms 24^a, 24^b. Each pair of arms comprise separate links, the said parts 24^a and 24^b respectively, which are pivotally connected at their adjacent ends and at their outer ends are pivotally mounted respectively on the head 23 and the casing 12. One of the arms 24^b is provided with a handle 26 by which the 40 arm 24^b may be moved to cause the casing 12 to move upwards and downwards.

The casing 12 is counter-balanced by cables 27 connected with the casing and extending upwards over pulley elements 28. The free ends of the 50 cables 27 are provided with a counter-weight 29.

The flexible crown and brim forming elements are connected in a particular manner with the projection 12^a. The connection comprises a tube 30 engaging through the casing 12 coaxial with 55

the projection 12^a. A nut 31 is threadedly mounted on the tube 30 and acts against the top of the casing 12. Another nut 32 is threadedly mounted on the lower end of the tube 30. This latter nut 5 clamps an edge portion 11^d formed on the upper edge of the crown forming element 11^b. A resilient washer or disc-shaped element 34 is interposed between the flange portion 11^d and the projection 12^a. The brim forming element 11^a and 10 crown forming element 11^b are integral with the flange portion 11^d (see Fig. 5).

A means is provided for supplying separate controlled hydraulic pressures to the crown and brim forming elements. This means essentially comprises a hydraulic substance system including a supply tank 36 from which there extends a supply pipe 37. This pipe is controlled with a valve 38 and connects with a pair of branch pipes 39 and 40. The pipe 39 is controlled with a valve 20 41 while the pipe 40 is controlled with a valve 42.

The pipe 39 connects with the tube 30 and with a discharge pipe 39^a. A hand release pressure valve 43 is interposed in the pipe system 39. The pipe 40 connects with a nipple 45 discharging into the hollow of the casing 12, and further connects with a discharge pipe 46 in which there is interposed a hand controlled relief valve 47. Pressure gauges 48 and 49 are respectively mounted upon the tube 30 and nipple 45. These 30 pressure gauges are adapted to show the pressure within the crown forming element 11^b and brim forming element 11^a.

By proper manipulation of the pressure valves 41 and 42 it is possible to build up the desired 35 high pressures in the crown forming element 11^b, and the desired lower pressures on the brim forming element 11^a.

The operation of the device is similar to pressure hydraulic substance machines generally 40 known prior to this specification. It distinguishes in the operation of the machine, by obtaining different pressures for the crown and the brim. A further feature of the invention resides in the 45 specific construction of the brim forming element 11^a and the crown forming element 11^b and the manner in which these parts are supported.

While I have illustrated and described the preferred embodiments of my invention, it is to be 50 understood that I do not limit myself to the precise constructions herein disclosed and the right is reserved to all changes and modifications coming within the scope of the invention as defined in the appended claims.

Having thus described my invention, what I 55 claim as new, and desire to secure by United States Letters Patent is:—

1. In a double pressure hydraulic substance machine for hats, a top forming section engageable into a complementary bottom forming section for shaping a hat form, comprising a casing having a depending central portion, a brim forming element having its edges fixedly attached to the edges of said casing, a crown forming element formed integrally with the bottom face of 60 said brim forming element, a flange portion formed integrally with said crown and brim elements and extending inwardly from the junction thereof, and means for fixedly attaching said 65 flange portion to said central portion to seal said crown element to form a hollow therein and to seal said brim element to form a hollow between said 70 brim element and the inner face of said casing, so that different pressures may be applied to said hollows and so apply different pressures 75 applied to said hollows and so apply different pres-

sures to the crown and brim of said hat form to correctly shape said hat form.

2. In a double pressure hydraulic substance machine for hats, a top forming section engageable into a complementary bottom forming section for shaping a hat form, comprising a casing having a depending central portion, a brim forming element having its edges fixedly attached to the edges of said casing, a crown forming element formed integrally with the bottom face of 10 said brim forming element, a flange portion formed integrally with said crown and brim elements and extending inwardly from the junction thereof, and means for fixedly attaching said flange portion to said central portion to seal said 15 crown element to form a hollow therein and to seal said brim element to form a hollow between said brim element and the inner face of said casing, so that different pressures may be applied to said hollows and so apply different pressures 20 to the crown and brim of said hat form to correctly shape said hat form, said brim forming element, said crown forming element and said flange portion all being formed integrally of 25 rubber or other yieldable waterproof substance. 25

3. In a double pressure hydraulic substance machine for hats, a top forming section engageable into a complementary bottom forming section for shaping a hat form, comprising a casing having a depending central portion, a brim forming element having its edges fixedly attached to the edges of said casing, a crown forming element formed integrally with the bottom face of 30 said brim forming element, a flange portion formed integrally with said crown and brim elements and extending inwardly from the junction thereof, and means for fixedly attaching said flange portion to said central portion to seal said 35 crown element to form a hollow therein and to seal said brim element to form a hollow between said brim element and the inner face of said casing, so that different pressures may be applied to said hollows and so apply different 40 pressures to the crown and brim of said hat form to correctly shape said hat form, comprising, a tube passing freely through said depending central portion, a nut threadedly engaged upon the end of said tube for clamping said flange portion between its top face and the bottom face of said 45 central portion, and a second nut threadedly engaged upon said tube intermediate of its ends and rotatable to move said tube upwards so said 50 nut will force said flange portion against said central portion.

4. In a double pressure hydraulic substance 55 machine for hats, a top forming section engageable into a complementary bottom forming section for shaping a hat form, comprising a casing having a depending central portion, a brim forming element having its edges fixedly attached 60 to the edges of said casing, a crown forming element integrally with the bottom face of said brim forming element, a flange portion formed integrally with said crown and brim elements and extending inwardly from the junction thereof, and means for fixedly attaching said flange 65 portion to said central portion to seal said crown element to form a hollow therein and to seal said brim element to form a hollow between said brim element and the inner face of said casing, 70 so that different pressures may be applied to said hollows and so apply different pressures to the crown and brim of said hat form to correctly shape said hat form, comprising a tube passing freely through said depending central portion, 75

a nut threadedly engaged upon the end of said tube for clamping said flange portion between its top face and the bottom face of said central portion, and a second nut threadedly engaged upon said tube intermediate of its ends and rotatable to move said tube upwards so said nut will force said flange portion against said central

portion, a disc-shaped element of resilient material interposed between said flange portion and the bottom face of said depending central portion to assist in frictionally maintaining said flange in position and to assist in sealing said hollows. 5

MORRIS SCHILDHAUS.
